(57) **CLAIM**

The ornamental design for a vehicle tailgate, as shown and described.

DESCRIPTION

FIG. 1 is a front left top perspective view of a vehicle tailgate according to the present invention.

FIG. 2 is a front left perspective view of the tailgate shown in FIG. 1.

FIG. 3 is a rear right top perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a front view of the vehicle tailgate shown mounted to a vehicle shown as de-emphasized environment thereof. Portions of the vehicle tailgate placed in broken line form no part of the claimed design. Areas de-emphasized and half-tone outside the broken line in FIG. 11 disclose environment only and form no part of the claimed design.
